ATTORNEY.

UNITED STATES PATENT OFFICE

JOHN J. REINHOLD, OF MARIETTA, PENNSYLVANIA

KNEADING DEVICE

Application filed May 8, 1930. Serial No. 450,612.

The present invention relates to body applicators and more particularly to a device for externally treating the organs contained in the abdominal cavity of the human body, 5 the walls of that cavity, muscles and other parts.

It has heretofore been proposed in various patented structures to simulate the action of the human fingers when giving massage and kneading treatments and while these mechanical substitutes may serve fairly satisfactorily for surface treatments, none has been efficient as a corrective of stomach and 15 intestinal disorders. It is one problem to provide an apparatus for restoring or increasing the circulation of the blood to build up broken-down tissues, but quite another problem to provide a mechanical means capable of effectively kneading the stomach and 20 intestines of a person. It is to this last problem that the present invention is directed and in solving it the invention has as a secondary result also produced better results in body 25 surface treatments.

Some of the objects of the present invention are to provide a body kneading apparatus which is pioneer in character and operation; to provide an apparatus for body kneading purposes which is operated and manipulated solely by the person using it; to provide a treating mechanism which functions to compress the stomach, intestines and other internal organs of the user to cause them 30 to be stimulated, revived and restored to perform their natural functions; to provide a treating apparatus to apply a succession of relatively heavy impressions upon the body of a patient; to provide a treating apparatus wherein a plurality of relatively heavy 35 masses are arranged in predetermined spaced relation so that when applied to the body undergoing treatment there are periods of applied pressures alternating with periods of no pressure; to provide a complete unitary pressure treating mechanism wherein no effort is 40 required of the user other than to draw the mechanism across the place to be treated; and to provide other improvements as will hereinafter appear.

50 In the accompanying drawing Fig. 1 rep-

resents a side elevation of a treating apparatus embodying one form of the present invention; Fig. 2 represents a top plan of the same; and Fig. 3 represents a section on line 3-3 of Fig. 1.

Referring to the drawing one form of the present invention consists of a hub 10 having an axial bore 11 to receive a stationary shaft 12 upon which the hub 10 is mounted for free rotation. The shaft 12 preferably 55 projects from opposite ends of the bore 11 to respectively receive the apertured middle portions of a bail 13 which extends in opposite directions from the hub 10 to provide two generally loop-shaped handles 14. Studs 60 15 are threaded into the ends of the shaft 12 to hold the bail 13 in place and the heads of these studs 15 are preferably rounded to give a neat finished effect. It will thus be 65 evident that the hub 10 is freely rotatable 70 about the shaft 12 and that it can be actuated as desired by alternately pulling the bail 13 from its end handles 14.

In order to cause the hub 10 to impart a series or succession of heavy impressions to 75 the body of a patient, a plurality of radially disposed weight members 16 are formed integral with the hub 10 but projecting equal distances from the axis of rotation to terminate in arc shaped faces 17 which are segments of the same sphere. As here shown there are three weight members 16 each having a length substantially equal to one sixth 80 of the circumference of the imaginary sphere so that between each adjacent pair of members 16 there is a radial space 18 having its mouth substantially equal to one one-sixth of the aforesaid circumference. The bounding walls 20 of each of these spaces 18 curve towards each other and then loop inwardly to 85 merge into the circumference of the hub 10. Thus the two ends, circumferentially considered, of each weight member 16, are rounded in a predetermined manner so that each 90 can roll against the flesh without presenting 95 any sharp angles.

For the purpose of eliminating direct contact of the weight members 16, which are preferably metal, with the body and giving an initial cushioning of the heavy impres-

sion, each member 16 has its working face covered with a pad 21 of rubber or other suitable yielding material which, in the present instance, is molded into position by providing a peripheral groove 22 in each member 16 to receive a pressed-in annular flange 23 on the inner side of each pad 21. The overall diameter of each pad 21 is greater than that of the member 16 upon which the pad is to seat so that in assembled condition an air chamber 24 is formed between the working face of each member 16 and the pad 21. In consequence of this each mass impression of a member 16 upon the yielding body results in a graduated application of the total weight instead of an abrupt dropping of the weight with an impact effect.

In operating the device of the present invention the patient assumes a reclining position with the parts of the body to be treated exposed for direct contact by the cushioned weight members 16. The handles 14 are now grasped and the device drawn back and forth across the body with its full weight applied to the parts undergoing treatment and the result is a succession of heavy impressions alternating with a succession of periods when no pressure is applied. Thus the effect of each weight member 16 is to begin its working impression with a cushioning action but as the weight rolls into its most effective position the cushion is compressed to give a more positive weight action, so that instead of having a mere surface massage action the weight really sinks into the body. Generally the abdomen is the part to be treated and the weight therefore is sufficient to project the abdominal wall inwardly so that the stomach, or intestines or other parts receive a direct compressive action. This inward projection of the flesh wall is sufficiently severe to stretch the projected and indented parts so that when the weight moves on and its place is taken by a space 18 these stretched parts rebound to normal position. This action is repeated as the device is drawn across the body to act upon different areas and a return travel of the device can work the same location again or by shifting the starting point it can work upon adjacent locations.

It will now be apparent that a complete unitary treating device of the kneading type has been devised whereby the internal organs of the body receive an effective working action designed and operative to stimulate and maintain them functioning in the natural manner. Furthermore by the use of relatively heavy masses, operating in succession, a direct kneading of the intestines is made possible which stirs up dormant conditions and positively eliminates clogging pockets and strictures.

While only a single form is shown in which this invention may be embodied, it is to be understood that the invention is not limited to

any specific construction, but might be applied to various forms without departing from the spirit of the invention or the scope of the appended claim.

Having thus described my invention, I claim:

A massaging apparatus comprising a frame forming a handle, a heavy metal body rotatably mounted within said frame having a relatively small central hub portion, radially arranged circular knobs of substantial area extending from said hub portion and each having outwardly flaring side walls terminating in an enlarged head portion with a contact area of a diameter substantially that of the width of the hub portion, and a concavo-convex resilient pad member mounted on the head portion of each of said knobs and having the concave side thereof spaced from the outer face of said head portion whereby a series of heavy cushioned blows are imparted to the surface to be treated when said apparatus is moved thereover.

Signed at Philadelphia, county of Philadelphia, State of Pennsylvania, this 28th day of April, 1930.

JOHN J. REINHOLD.
